FRAME FOR HANDBAGS

Max H. Storch, Belle Harbor, N. Y., assignor to
Harry E. Darr, Belle Harbor, N. Y.

Application January 24, 1944; Serial No. 519,558

4 Claims. (Cl. 150—29)

This invention relates to new and useful improvements in composite frames for hand bags.

An object of this invention is to provide a simple and durable composite frame construction having means whereby edge portions of the bag leather or other flexible bag material may be easily and securely attached to the frame.

Another object of this invention is to provide means for quickly and rigidly securing phenolic or similar ornamental frame members and metallic frame members co-acting in unitary relation to grip the body fabric of hand bags.

Another object of this invention is to provide an ornamental plastic frame member of substantially solid rectangular cross-section, the inner upright face of which has a groove coextensive therewith and the outer face of which has a recess, the upper walls defining the groove and the recess being in substantially equally spaced relation from the lower face of the plastic frame member.

Another object of this invention is to provide a channel-shaped metallic frame member adapted to embrace a portion of the plastic frame member and having arms of equal length, one of the arms having an inwardly bent edge adapted to enter the groove in the plastic frame member and the other arm having an angularly extending side with an inwardly bent edge adapted to enter the recess in the plastic frame member.

Another object of this invention is to provide a hand bag fabric having a reinforcing cord stitched to an edge portion thereof and forming an outlying edging, the edging being considerably thicker than the hand bag fabric and of a size to substantially fill the recess in the plastic frame member.

Another object of this invention is to provide a composite hand bag frame adapted to equally grip or secure all thicknesses of hand bag material, and so that a single type composite frame can be utilized for all hand bags regardless of the thickness of the material of the hand bag body such as cloth, silk or leather.

Another object of this invention is to provide a modified form of composite frame wherein the attachable edge portions of the body fabric of the hand bag are without a reinforcing cord, and to provide a double wedge action interlock which causes the said edge portions to be securely held against the horizontal plane surface defining the top of the recess and against a vertical plane surface defining an inner side wall of the recess, this double wedge action serving to firmly secure the body fabric against removal from the com-

posite frame when the body fabric of the hand bag and the composite frame are in assembled relation.

With the above and other objects in view, the invention will be hereinafter more particularly described, and the combination and arrangement of parts will be shown in the accompanying drawing and pointed out in the claims which form part of this specification.

Reference will now be had to the drawing, wherein like numerals of reference designate corresponding parts throughout the several views, in which:

Figure 1 is a perspective view of a hand bag made in accordance with my invention.

Figure 2 is a side elevation of the composite frame with a metal frame member partly broken away, and showing the manner of attaching the metal frame member to its co-acting ornamental frame member.

Figure 3 is a transverse section taken along line 3—3 in Figure 2, on an enlarged scale.

Figure 4 is a view similar to that shown in Figure 3, illustrating an edge portion of the body fabric of the hand bag and its lining attached to the composite frame.

Figure 5 is a view of an edge portion of the hand bag body fabric, showing a reinforcing cord stitched thereto and forming an outlying edging.

Figure 6 is a cross-sectional view of a modified composite hand bag frame.

In the illustrated embodiment of the invention, the numeral 10 indicates a hand bag comprising a composite frame 11 and a bag body 12.

The composite frame 11 comprises ornamental main frame members 13, 14, which are pivotally mounted at 15, 15. The main frame members 13, 14 are preferably made of solid phenolic or similar ornamental material which is hard and non-crimpable.

Each main frame member comprises vertical sides 16, 16. The pivotal or hinge mountings 15, 15, connect the lower end portions of the vertical sides 16 so as to cause the inner faces 17 of the main frame members 13, 14, to come into contacting relation with each other when the hand bag 10 is in closed position.

As best shown in Figures 3 and 4, each main frame member has a groove 18 in its inner face and a recess 19 in its outer face 20. In the embodiment shown, the upper walls defining the groove 18 and the recess 19 are in equally spaced-apart relation from the lower face 21 of the main frame member.

In conjunction with the plastic main frame members 13, 14, are a pair of metal frame members 22 of substantially channel-shaped cross-section. The frame members 22 have vertical side walls 23 extending at right angles to a connecting horizontal portion 24. The side walls 23 of the metal frame members are disposed in parallel relation.

Each of the frame members 22 has parallel arms 25 and 26. The arm 25 has an inwardly bent free edge 27 designed to enter into engagement with the groove 18 in the inner face of the respective main frame members 13 and 14.

The arm 26 has an angularly extending side portion 28, at the free end of which the edge is inwardly bent to provide a lateral extension 29.

In assembled relation, when a metal frame member 22 is forcibly applied to a main frame member, the metal frame member tightly embraces the lower portion of the main frame member and the lateral extension 27 seats in the groove 18. The metal frame member is then rigidly connected with the ornamental main frame member.

In Figure 5 is shown a form of connecting edging with which the body fabric of hand bags may be improved. This edging may be utilized for the purpose of securing all makes of body material, particularly all thicknesses of body material, such as cloth, silk or leather to a single type composite frame.

For the above purpose, a substantially non-compressible reinforcing cord 30 is positioned in outlying and contacting relation with the hand bag body fabric 12 and secured to the said fabric preferably by means of zig-zag stitching 31. The stitching shown, pierces the body fabric and the cord successively in two different and slightly spaced longitudinal lines. The cord 30 is considerably thicker than the joint thickness of the hand bag fabric 12 and the lining fabric 32 and of a size to substantially fill the recess 19 in the coacting ornamental main frame member, as best shown in Figs. 3 and 4. The cord may have longitudinal reinforcement wires.

In assembling the bag body in unitary relation with the composite frame, the corded edge portion of the hand bag fabric is inserted into the recess 19 and pressure is applied against the angularly extending portion 28 of the arm 26 in a direction facing the recess. This pressure causes the bent laterally extending edge 29 to press the body fabric into the recess 19 and provides interlocked engagement of the composite frame with the body material and prevents removal of the body material of the hand bag from the composite frame.

Figure 6 shows a modified form of the invention wherein the attachable edge portion of the body fabric is without a reinforcing cord. As shown, a cavity 19' is provided having a lesser lateral depth than the cavity 19. The cavity 19' is of a size designed to receive the body fabric 12' and a coacting lining fabric in tight engagement when the upper portion 28' of the arm 26' is forced into the said cavity.

The bent free edge or flange 29' is in such close relation with the top wall of the cavity 19' as to cause a wedging action against the body fabric. The body fabric is held wedged against a horizontal plane surface defining the top of the cavity, and against a vertical plane surface defining an inner side wall of the said cavity.

In the illustrations shown, the securing edges are not visible on the outside of the composite frame, and the body fabric and lining are securely

held in interlocked relation all the way along their marginal extent by a continuous fastening.

A further means of augmenting the grip on the body material may be had by applying glue or cement to the securing edge portions of the body material inside the cavity 19'.

It is to be noted that the recess or cavity in the solid frame member is of rectangular form so as to provide adjacent walls in perpendicular relation, thus providing the horizontal plane surface defining the top of the recess or cavity and the vertical plane surface defining the inner side wall of the recess or cavity against which the desired double wedge action takes place when the composite frame members are in assembled and interlocked relation from opposite sides.

It is also to be noted that the inwardly bent edge 29' of the angularly extending and inwardly bendable portion 28' of the side arm 26' is in right-angular relation with said side arm. This right-angular portion 29' is designed to move into close contacting relation with the horizontal and vertical plane surfaces defining the top and a vertical side wall of the recess 19'.

25 In accordance with the patent statutes I have described and illustrated the preferred embodiment of my invention, but it will be understood that various changes and modifications can be made therein without departing from the spirit 30 of the invention as defined by the appended claims.

I claim:

1. In a composite hand bag frame, a transparent plastic frame member of substantially 35 solid rectangular cross-section, said plastic frame member having a groove in its inner face and a recess in its outer face, the upper walls defining said groove and said recess being in equally spaced relation from the lower face of said plastic frame member, a channel-shaped metallic frame member adapted to embrace a portion of said plastic frame member and having arms of equal length, one of said arms having an inwardly bent edge adapted to enter said groove, the other arm having an angularly extending side with an inwardly bent edge adapted to enter said recess, and a hand bag fabric having a reinforcing cord stitched to an edge thereof and forming an outlying edging, said edging being considerably thicker than said hand bag fabric and of a size to substantially fill said recess, whereby upon inserting said corded edging into said recess, pressure against said angular side in a direction facing said recess will cause the bent edge of said side to come into mechanically interlocked relation with said corded edge and prevent removal of said hand bag fabric from said composite frame, both bent edges of said metallic frame member extending in laterally interlocked unitary relation with said plastic frame member.

2. In a composite hand bag frame, a plastic frame member of substantially solid rectangular cross-section, said plastic frame member having a groove in its inner face and a recess in its outer face, the upper walls defining said groove and said recess being in equally spaced relation from the lower face of said plastic frame member, a channel-shaped metallic frame member adapted to embrace a portion of said plastic frame member and having arms of equal length, one of said arms having an inwardly bent edge adapted to enter said groove, the other arm having an angularly extending side with an inwardly bent edge adapted to enter said recess, means for securing an edge portion of hand bag mate-

rial in said recess, pressure against said angular side in a direction facing said recess causing said bent edge of said angular side to come into interlocked relation with said fabric edge and prevent removal of said hand bag fabric from said composite frame, both bent edges of said metallic frame member extending in laterally interlocked unitary relation with said plastic frame member when in assembled relation.

3. In a composite hand bag frame, a plastic frame member of substantially solid rectangular cross-section, said plastic frame member having a groove in its inner face and a recess in its outer face, the upper walls defining said groove and said recess being in equally spaced relation from the lower face of said plastic frame member, a channel-shaped metallic frame member adapted to embrace a portion of said plastic frame member and having arms of equal length, one of said arms having an inwardly bent edge adapted to enter said groove, the other arm having an angularly extending side with an inwardly bent edge adapted to enter said recess, whereby upon inserting an edge portion of hand bag fabric into said recess, pressure against said angular side in a direction facing said recess will cause the bent edge of said side to come into interlocked relation with said fabric edge and prevent removal of said hand bag fabric from said composite frame, both bent edges of said metallic frame member extending in laterally interlocked unitary relation with said plastic frame member when in said assembled relation.

4. In a composite hand bag frame comprising

a frame member of substantially solid rectangular cross-section, said solid frame member having a groove in its inner face and a recess in its outer face, a channel-shaped metallic frame member applied externally of said solid frame member, said metallic frame member having arms adapted to embrace a portion of said solid frame member, one of said arms having an inwardly bent edge adapted to enter said groove, the other arm having an angularly extending side with an inwardly bent edge adapted to enter said recess, whereby upon inserting an edge portion of hand bag fabric into said recess, pressure against said angular side in a direction facing said recess will cause the bent edge of said side to come into interlocked relation with said fabric edge and prevent removal of said hand bag fabric from said composite frame, both bent edges of said metallic frame member extending into said solid frame member and being in interlocked unitary relation with said solid frame member when in assembled relation, said recess being of rectangular form and providing a horizontal plane surface defining the top of said recess and a vertical plane surface defining an inner side wall of said recess, the said inwardly bent edge of said angularly extending and inwardly bendable side arm being in right-angular relation with said side arm and causing a double wedge action against said surfaces and said body fabric to be securely clamped against removal from said composite frame when in assembled relation.

MAX H. STORCH.
